UNITED STATES PATENT OFFICE.

NILS D. LEVIN, OF COLUMBUS, OHIO, ASSIGNEE TO THE JEFFREY MANUFACTURING COMPANY, A CORPORATION OF OHIO.

BIT-HOLDER FOR MINING-MACHINES.

1,140,173.

Specification of Letters Patent. Patented May 18, 1915.

Application filed January 8, 1909. Serial No. 471,293.

To all whom it may concern:

Be it known that I, NILS D. LEVIN, a citizen of the United States, residing at Columbus, in the county of Franklin and State of Ohio, have invented certain new and useful Improvements in Bit-Holders for Mining-Machines, of which the following is a specification, reference being had therein to the accompanying drawing.

10 This invention relates to improvements in devices for attaching bits or cutters to the cutting chains or wheels of mining machines.

15 The object of the invention is to furnish a simple and effective, and at the same time readily adjustable means for holding the bits.

20 In the drawings—Figure 1 is a plan view of a section of chain showing one bit or cutter attached. Fig. 2 is an elevation of the section of chain shown in Fig. 1. Fig. 3 is a sectional view through the line $x-x$ of Fig. 1.

I do not wish to confine myself to the 25 chain shown in the drawings which is used merely for the purpose of illustration.

A represents one of a series of links of the mining machine chain and is adapted to carry the cutter or bit D.

30 B—B and C—C are other links connected to the link A by the pins b and c.

E is a boss or lug on the link A and is either cast or forged integrally therewith or secured in any other suitable or preferred 35 manner.

F is a hole extending through the link A and the boss E at an angle to the line of motion of the chain, and is formed to receive the shank of the bit. The boss E is 40 provided with a hole G at an angle to the hole F and adjacent thereto. This hole is tapering in form and is adapted to receive a key or cotter H which is similarly tapered. One edge of this key is provided with a 45 series of longitudinal teeth H'. The hole G is so disposed in relation to the hole F that as the tapered key H is forced into it the longitudinal teeth of the key will be brought into engagement with similarly disposed teeth K formed on the shanks of the 50 bit, and adapted to mate with the teeth of the key. The bit shank is also provided with other teeth K' on the side opposite to the teeth K so that the bit may be attached 55 to the chain with the working point L pro-

jecting in either direction to correspond with the proposed direction of motion of the chain.

When it is desired to adjust or replace the bit, assuming it to be in position as shown 60 in the drawings, it is only necessary to drive back the wedge shaped key H, thus permitting the disengagement of the teeth H', and K or K' and leaving the bit free to be 65 adjusted in the hole F or entirely removed if desired. When the bit has been adjusted or replaced, as the case may be, the key H is driven back into the hole G, the converging sides of which force the teeth of the key 70 into engagement with the teeth of the bit, thus securely locking the latter in position.

It will be observed that there are important advantages incident to the location of the wedge in the manner shown and described. The wedge lies substantially parallel to the lines of movement and its larger end is foremost. In the operation of a mining machine it frequently happens that the parts adjacent to the cutters come in contact with external objects, such as lumps 75 of coal, pieces of slate, etc., which may accidentally fall into the kerf or otherwise come into the path of the moving parts. The arrangement of the wedges is such that accidental contact of the wedges with these 80 external objects will serve to drive the wedges more firmly into their places. It will be apparent that this result cannot be obtained with any other arrangement or 85 with any other positions of the wedges. It will furthermore be observed that each bit 90 shank contacts at its forward and rear edges directly with the walls of the aperture in which it is located so that the stresses of cutting are transmitted directly to the heavy 95 bit-carrying parts independently of any intermediate holding devices such as set screws, latches, wedges, etc.

What I claim is,

The combination in a mining machine bit 100 and holder, of a bit carrying element having an inward extending aperture for receiving a bit shank and a second aperture at one side of the first aperture but communicating therewith, the first aperture being 105 at an angle to the line of motion of the carrying element and the second aperture being substantially parallel with the said line, a bit having its shank positioned in the first or shank receiving aperture, and a rear- 110

ward tapering friction held wedge in the second aperture, one side of the wedge being in forced engagement with the shank of the bit and the opposite side being in forced engagement with the aperture wall opposite the shank, the whole arrangement being such that any accidental engagement of the moving wedge with relatively stationary

external objects will tend to force the wedge into firmer engagement with the bit shank. 10

In testimony whereof I affix my signature, in presence of two witnesses.

NILS D. LEVIN.
